UNDERGARMENT

Minerva M. Webster, Cleveland, Ohio

Application February 19, 1941, Serial No. 378,175

2 Claims. (Cl. 2—224)

The invention relates to undergarments, and the improvements in this type of garment are particularly illustrated and described in the instant application as applied to a woman's undergarment designed to be worn with short fur jackets or winter suits. The improvements as thus applied provide an undergarment for winter wear which, while being of light weight, and non-bulky and non-cumbersome, nevertheless serves to keep the legs, and particularly the knees, adequately warm.

The improved women's undergarment can readily be laundered and, in that form thereof hereinafter fully described which includes a light weight animal skin interlining which could not be cleaned by ordinary laundry methods, can be readily taken apart for laundering of the outer garment portion and then again readily assembled for continued use.

The annexed drawings and the following description set forth in detail certain means embodying my invention, such disclosed means constituting, however, only two of the various forms in which the principle of the invention may be embodied.

In said annexed drawings:

Figure 1 is an elevation of a duplex pants portion of the improved women's undergarment, the view showing this duplex pants portion turned inside out with reference to its final position in the garment when the latter is being worn;

Figures 2, 3, and 4 are traverse sections, taken, respectively, in the planes indicated by the lines 2—2, 3—3, and 4—4, Figure 1;

Figure 5 is a front elevation of an animal skin interlining forming a second portion of the improved garment, this view also showing an inside out position with reference to its final position in the garment when the latter is being worn;

Figure 6 is a rear elevation of the animal skin interlining;

Figures 7 and 8 are transverse sections, taken, respectively, in the planes indicated by the lines 7—7 and 8—8, Figure 5;

Figure 9 is a front elevation of the two garment portions shown in Figures 1 and 5 after they have been initially assembled, this assembly consisting in positioning the animal skin interlining around the upper part of the duplex pants portion of the garment;

Figure 10 is a rear view of the upper part of the assembly shown in front view in Figure 9;

Figure 11 is a fragmentary transverse sec-

tion, taken in the plane indicated by the line 11—11, Figure 9;

Figure 12 is a view showing the assembly of Figure 9 after the lower part of the duplex pants portion of the garment has been pulled up over the interlining which surrounds the upper duplex pants portion in Figures 9 and 10, Figure 12 also showing this pulled up lower part of the duplex pants portion fastened to the upper part of the duplex pants portion above the top edge of the interlining;

Figure 13 is a fragmentary transverse section, taken in the plane indicated by the line 13—13, Figure 12;

Figure 14 is a longitudinal section, taken in the plane indicated by the line 14—14, Figure 1;

Figure 15 is a longitudinal section, taken in the planes indicated by the line 15—15, Figure 5;

Figure 16 is a longitudinal section, taken in the plane indicated by the line 16—16, Figure 9;

Figure 17 is a longitudinal section, taken in the planes indicated by the line 17—17, Figure 12;

Figure 18 is an elevation of the complete garment assembled as shown in Figure 12, but turned inside out from the assemblage thereof shown in Figure 12, this Figure 18 showing the garment as it appears when it is ready to put on;

Figure 19 is a longitudinal section, taken in the planes indicated by the line 19—19, Figure 18;

Figure 20 is a fragmentary transverse section, taken in the plane indicated by the line 20—20, Figure 18;

Figure 21 is an elevation of a modified form of women's undergarment, ready to put on, the modification consisting in a certain assembly of the garment portions such as will make of the garment a permanent assembly; in other words, it need not be taken apart for laundering purposes; and

Figure 22 is a longitudinal section, taken in the planes indicated by the line 22—22, Figure 21;

Referring to the annexed drawings in which the same parts are indicated by the same respective numbers in the several views, and particularly referring first to the form of garment shown in Figures 1—20, which is a form comprised of separable garment portions, a duplex pants portion 1, Figure 1, consists of a double bloomer or double bifurcated skirt, viz., an upper part 2 and a lower part 2' joined at the ends of leg portions 3 and 3' so as to form what is, in effect, an upper bloomer-appearing portion and a lower

upside down bloomer-appearing portion joined by an intermediate continuous bifurcated or leg portion. The upper part 2 and the lower part 2' of the garment portion 1 are not of the same length, but the upper part 1 is formed with a terminal member 4 which, in the complete garment, forms a waist-encircling member and extends upwardly beyond the doubled thickness formed by folding the parts 2 and 2' upon each other in a manner and for a purpose hereinafter described and particularly shown in Figures 12 and 18. Of course, the whole outer garment portion 1 may be in a single piece and, probably, preferably so, but has been described as of two joined similar pants members for the purpose of clearly indicating the particular structure of this garment portion 1.

The adjoining portions 11 and 11' of the leg members 3 and 3' are preferably of a quite elastic nature, preferably of knitted material, so as snugly to encase the legs of the wearer below the knees, when the garment is being worn, as will be hereinafter fully described. The main body of the garment portion 1 is preferably made of light weight silk, such as taffeta, satin, or of jersey or crepe material, or of any suitable light weight elastic material. The waist line 4' at the upper edge of the member 4 may either be fitted or buttoned at the side, or held in with elastic.

Adjacent the lower edge of the waist member 4 are two superimposed rows of fastener elements 5 and 6 secured to a tape 7 or other suitable foundation strip for the fasteners. Also secured to a tape 9 adjacent the bottom of the pants part 2', as shown in Figure 1, are a row of fastener elements 8 which, in a manner hereinafter fully described, are adapted to cooperate with the row of upper fasteners 6 for securing together the pants parts 2 and 2' when they are folded together. In the median or folding line of the pants parts 2 and 2', midway of the top and bottom of the knitted material parts 11 and 11', are a series of transverse fasteners 10.

Cooperating with the duplex pants portion 1 to form the complete garment is an interlining 15, Figure 5, which also is of pants formation and has a row of fastener elements 16 secured to a tape 17 adjacent its upper edge, which fastener elements 16 cooperate with the row of fastener elements 5 on the pants portion 1, Figure 1, as hereinafter fully described. The interlininig 15, which is preferably a light weight animal skin, such as doeskin or chamois, has discontinuous or incomplete leg portions 18, Figure 8, and a crotch member 19 at the front, shown in Figures 5 and 8 in open position, provided with elastic bands or straps 23, the rear of the crotch region of the interlining 15 being open, in the position of the garment shown in Figure 5, as clearly appears in Figure 8. Bordering the rear open crotch region of the interlining 15 is a tape 20, Figures 6 and 8, carrying a series of fastener elements 21, and bordering the bottom of the front crotch member 19 is a tape 22 having depending therefrom the straps or bands 23 which are formed with terminal fastener elements 24. The bottom edges of the leg parts of the interlining 15 are provided with tapes 25 having fastener elements 26. The ends of the tape 20 are fastened to the tapes 25. These tapes 25 have disconnected ends which can be fastened together by end fastener elements 26' to define the leg portions of the complete garment just below the knees of the wearer.

The above description outlines the structures of the garment portions which when assembled make the complete garment.

The first step in the assembling of the duplex pants portion 1 and the interlining 15 to make the whole garment is to lay out the duplex pants 1, as shown in Figure 1, which is an inside out position, as compared with its position in actual use, and then pull the interlining 15 over the duplex pants 1, as shown in Figures 9 and 10, and fasten together the fastener elements 5 and 16. Then the fastener elements 10 and 26 are secured together. Then the two pairs of fastener elements 26' are fastened together and, finally, the fastener elements 24 upon the straps or bands 23 are secured to the fastener elements 21. The garment then appears front and rear as seen respectively in Figures 9 and 10. It will be noted that the fastening of the elements 26' has closed the leg portions of the interlining 15 and that a fullness of material has been provided by the front crotch member 19 which will prevent the garment binding when being worn, particularly prevent binding when the wearer bends over or sits down.

Then the lower part 2' of the duplex pants 1 is pulled up over the interlining 15 and the fastener elements 8 secured to the fastener elements 6, as shown in Figure 12. The garment is then completely assembled, but, for use, is turned inside out so as to produce the position thereof shown in Figure 18.

In the form of garment shown in Figures 21 and 22, it is presumed that the interlining is a skin or other material that will withstand dry cleaning or other usual laundering operations so that it would be unnecessary to take the garment apart for laundering purposes. Therefore, the interlining is permanently stitched into the outer parts, the structure and assembly being otherwise the same as those shown in the form of garment illustrated in Figures 1-20. The stitching seams between the interlining and the outside part of the duplex pants are indicated by the number 30, Figures 21 and 22, the seam between the inside part of the duplex pants and the outside part thereof by the number 31, and the upper edge of the inside part of the duplex pants by the number 32, and the top of the interlining by the number 33.

What I claim is:

1. An undergarment comprising a two-ply member providing inner and outer garment surfaces, said member being formed from a blank having body end portions, a central continuous leg portion and crotch portions intermediate said central leg portion and said end body portions, the member being assembled by folding said blank transversely of said leg portion, an interliner disposed intermediate said inner and outer surface portions and having body and leg portions respectively aligned with similar portions of the two-ply member, said interliner also having a loose crotch flap provided with flexible depending straps and means for detachably fastening the straps to the sides and upper edge of the flap, and means for securing the interliner with in the two-ply member.

2. An undergarment comprising a pants member having body, crotch, and leg portions and extended at one end to encircle the waistline of the wearer and at the other end to reach immediately below the knees, a second pants member having crotch and leg portions aligned with similar portions of the first-mentioned pants mem-

ber and also having a body member secured at its upper edge to the first-mentioned pants member somewhat below the waistline, said second-mentioned pants member being also secured adjacent its bottom edge to the bottom edge of the first-mentioned pants member, and a third pants member of substantially the same length as the second-mentioned pants member and having

body, crotch, and leg portions aligned with similar portions of the second-mentioned pants member, said third-mentioned pants member being secured at its upper and lower edges to the first-mentioned pants member with the second-mentioned pants member therebetween and forming an interlining.

MINERVA M. WEBSTER.
